UNITED STATES PATENT OFFICE

152,839

DESIGN FOR A RADIO PHONOGRAPH
CABINET

Leland George Stone, Fort Wayne, Ind., assignor
to The Magnavox Company, Fort Wayne, Ind.,
a corporation of Delaware

Application February 20, 1947, Serial No. 137,052

Term of patent 7 years

(Cl. D56—4)

To all whom it may concern:

Be it known that I, Leland George Stone, a citizen of the United States, residing at Fort Wayne, in the county of Allen and State of Indiana, have invented a new, original, and ornamental Design for a Radio Phonograph Cabinet, of which the following is a specification, reference being had to the accompanying drawing, forming a part thereof.

In the drawing:

The single drawing figure is a front perspective view of my radio phonograph cabinet.

The characteristic feature of the design is the molding which is rounded in cross section which extends across the top margins and continues downwardly on all four corners of the cabinet.

I claim:

The ornamental design for a radio phonograph cabinet, substantially as shown and described.

LELAND GEO. STONE.
